UNITED STATES PATENT OFFICE.

JULES FAGARD, OF LIEGE, BELGIUM.

CARBURETER FOR INTERNAL-COMBUSTION ENGINES.

1,109,974.

Specification of Letters Patent.

Patented Sept. 8, 1914.

Application filed January 9, 1912. Serial No. 670,213.

To all whom it may concern:

Be it known that I, JULES FAGARD, subject of the King of Belgium, and residing at Liege, Belgium, have invented certain new and useful Improvements in Carbureters for Internal-Combustion Engines; and I do hereby declare the following to be a full, clear, and exact description of the invention, such as will enable others skilled in the art to which it appertains to make and use the same.

In internal combustion engines starting is often difficult when the engine is cold. Moreover, running at slow speeds is usually defective by reason of the cooling which results from the diminished activity of the engine, and which gives rise to the formation of frost which obstructs, and ultimately completely chokes up the small 20 passages.

The present invention has for its object an arrangement which permits of obtaining easy starting and perfect picking up and running at slow speeds. This object is attained by means of a supplementary spraying nozzle supplied with warm air, the throttle valve being arranged so as to admit, as it commences to open and before the principal spraying nozzle comes into operation, a supply of air for correcting the over-rich initial carburation. Moreover the arrangement is such that the auxiliary nozzle cannot receive fuel when the engine is running at normal and high speeds, so as to prevent loss of fuel resulting from the suction produced by the sudden closing of the valve. This carbureter is also arranged so as to permit of easily removing the two nozzles and so as to facilitate their cleaning.

The accompanying drawing represents, by way of example, a carbureter constructed according to this invention.

Figure 1 is a diagrammatic view, and Fig. 2 is a vertical section.

The carbureter shown comprises a chamber *a* in the upper part of which is arranged the throttle valve *b*. The fuel coming from the constant level fuel reservoir *c* passes to the principal nozzle *e* by the pipe *d*; the hot air is admitted at *f* and the gaseous mixture passes to the engine by pipe *g*. The auxiliary nozzle *h* which delivers the fuel into the pipe *g* below the valve *b*, is supplied from the pipe *d* as hereinafter described.

The new arrangement is such that when the valve *b* is opened, for normal or fast running, the flow of fuel in the carbureter has the effect of preventing the supply to the auxiliary nozzle *h*, to avoid producing a mixture which is too rich when the engine is running at the above speeds, and which would also cause waste when the valve *b* is suddenly opened. With this object, the auxiliary tube *k*, leading from the fuel tube *d*, is open to the atmosphere at *i* and the nozzle *h* receives the fuel through a tube *l*, which extends into the tube *k* to a suitable level. The air is supplied to the auxiliary nozzle *h* by a passage *m* leading from the inlet *f*.

The passage *d* is divided into two parts by the branch tube *k*; the one part *p*, located between the constant level fuel reservoir *c* and the tube *k*, is of a length suitable for the quantity of fuel to be supplied to the engine, so that for a certain quantity of fuel supplied to the nozzle *e*, the resistance of this passage produces a depression in the tube *k* in which the tube *l* is situated. Owing to this fact the level of the fuel in the said tube *l* falls more and more and in proportion to the increase in the number of revolutions of the engine, that is to say, in proportion to the rate of the fuel from the reservoir toward the nozzle *e*.

The length and diameter of the tube *q* are such that the level cannot fall in the tube *k* so as to completely empty the latter; moreover the tube *l* extends into the tube *k* so that its lower end is situated at a height corresponding to the level to which the fuel falls when the engine is running at the most efficient speed.

The lower end of the tube *k* communicates with the passage *d* by an orifice *o* which determines, by its dimensions, the rate of filling of the said tube *k* after the valve *b* has been closed, and determines at the same time maximum consumption of fuel by the nozzle *h*.

If only the resistance of the passage *p* be opposed to the flow of fuel from the constant level reservoir *c* to the tube *k* and the tube *d* is of a greater diameter or of a less length from the tube *k* to the nozzle *e* than the part *q* the fuel will be supplied to the nozzle *h* at slow engine speed (when the said nozzle alone is in operation) first of all from the part of the pipe *d* that supplies the nozzle *e*; it will result from this that the level

will fall to a considerable extent in the nozzle *e* and the latter will be in an unfavorable condition for working when the valve *b* is opened. To obviate this possible disadvantage it is sufficient to give to the part *q* of passage *d*, between the tube *h* and nozzle *e*, the same diameter but a greater length than the part *p*, so that the suction of the fuel from the nozzle *e* causes a flow of fuel from the constant level reservoir *c* more readily than from the passage *q* leading to the nozzle *e*.

With the same object the passage *q* can be a smaller diameter than *p*, without its being necessary to give to the said passage *q* a greater length; it is equally possible to replace the passages *p* and *q* by simple orifices, that corresponding to *p* having an opening smaller than the other.

20. In order to reduce the length of the passages *q* and *p*, while still obtaining the desired resistances, baffle plates can be provided in the passages, or the latter can be made of helical form, so that the fuel has to flow through a long course in traveling a short distance.

The arrangement represented in Fig. 2 shows a method of carrying out the invention. The length and diameter of the passage *p*, is calculated so as to offer, the desired resistance to the flow of the fuel, while the resistance of the tube *q* is increased by a helix *n* carried by a screw plug *r* located in a bend of the passage *q* and capable of being easily removed; moreover, the reduced opening *o* and the nozzle *h* are made in removable screw plugs *s* and *t*. The nozzle *e* is carried by a cone *j* forming a tight joint and drilled to form a fuel passage. This cone is secured in place in the carbureter by a nut or screwed key *u*, provided with a rectangular recess *v* which can be engaged with the similarly shaped ends of the cone *j* and of the plugs *r*, *s*, *t*. The nut *u*, when it is turned, acts as a key and permits of the ready disassembling of the carbureter.

Having fully described my invention, what I desire to claim and secure by Letters Patent is:

50. 1. In a carbureter for internal combustion engines, the combination of a casing, a hydrocarbon reservoir, a main nozzle, an auxiliary nozzle, conduits connecting the reservoir and nozzles, and a throttle valve controlling the discharge of vapor from the casing, the connections between the reservoir and nozzles automatically rendering the auxiliary nozzle operative only when the throttle valve is positioned to cause an engine connected with the carbureter to run at less than its normal speed.

2. In a carbureter for internal combustion engines, the combination of a casing, a hydrocarbon reservoir, a main nozzle, an auxiliary nozzle, a conduit for supplying

hydrocarbon from the reservoir to both nozzles, and means interposed between said conduit and the auxiliary nozzle whereby the latter is automatically rendered inoperative when the main nozzle is exposed to the suction created by normal speed of the engine connected with the carbureter and is alone operative when starting the engine.

3. In a carbureter for internal combustion engines, the combination of a casing, a hydrocarbon reservoir, a main nozzle, an auxiliary nozzle, a conduit for supplying hydrocarbon from the reservoir to both nozzles, and means for retarding the passage of hydrocarbon from the supply conduit to the auxiliary nozzle, whereby said auxiliary nozzle is automatically rendered inoperative when the main nozzle is exposed to the suction created by normal speed of the engine to which the carbureter is connected.

4. In a carbureter for internal combustion engines, the combination of a casing, a hydrocarbon reservoir, a main nozzle having a supply conduit connected with the reservoir, a branch conduit connected with said supply conduit, an auxiliary nozzle having its fuel supply pipe extending into said branch conduit, a throttle valve controlling discharge of vapor from the casing, and means controlling the passage of hydrocarbon through said supply conduit whereby when the throttle is positioned to cause an engine connected with the carbureter to operate at or above normal speed the amount of hydrocarbon entering the branch conduit will be insufficient to permit operation of the auxiliary nozzle.

5. A carbureter for internal combustion engines comprising, in combination with the principal nozzle, an auxiliary nozzle receiving its fuel from the principal supply pipe with which it communicates by a plug having a small orifice; the principal nozzle being carried by a conical plug secured in place by a screwed member which is provided with a recess which can be engaged with the projecting ends of the plugs of the principal nozzle, of the auxiliary nozzle, of the tube leading to the latter from the supply pipe, and of the helix for increasing the resistance to the flow of fuel through certain parts of the principal supply pipe.

6. In a carbureter for internal combustion engines, the combination of a casing, a hydrocarbon reservoir, a conduit leading from the reservoir and having branches for supplying hydrocarbon to both nozzles, a throttle valve adjustable to permit only one of the nozzles to discharge hydrocarbon when starting an engine connected with the carbureter, the relative proportions of the branches of the hydrocarbon supply conduit being such that when the throttle valve is adjusted to expose the second nozzle to

the suction created by the engine running at or above normal speed the supply of hydrocarbon to the first said nozzle will be automatically cut off.

- 5 7. In a carbureter for internal combustion engines, the combination of a casing, a hydrocarbon reservoir, a main nozzle connected with the reservoir, a chamber *k* open to the atmosphere and communicating 10 with the hydrocarbon supply conduit, an auxiliary nozzle having its hydrocarbon supply duct opening into the chamber *k*, a throttle valve adapted to be positioned to expose the auxiliary nozzle only to the

suction created by an engine connected with the carbureter when starting or running at low speed, the supply of hydrocarbon to the chamber *k* being automatically cut off as the throttle is adjusted to expose the main nozzle to the suction created by the engine when running at or above normal speed.

In testimony whereof I affix my signature in presence of two witnesses.

JULES FAGARD.
